VENTED LIQUID DISPENSER

Richard W. Beall, Jr., Hermosa Beach, Calif.
Application January 19, 1956, Serial No. 39,844

Term of patent 14 years
(Cl. D62—2)

Figure 1 is a side elevational view of a vented liquid dispenser, illustrating my new design;

Figure 2 is a perspective view;

Figure 3 is a perspective view in an inverted position;

Figure 4 is a bottom plan view taken in the direction of the arrow 4 shown in Figure 1; and

Figure 5 is a top plan view taken in the direction of the arrow 5 shown in Figure 1.

I claim:

The ornamental design for a vented liquid dispenser, substantially as shown.
